James Leffel of Springfield Ohio
Letters Patent No 4448 Dated Feb 24 1852.

The schedule referred to in these Letters Patent and making part of the same

To all whom it may concern,

Be it known that James Leffel of Springfield in the County of Clark of state of Ohio have made a new and ornamental design for the plates of cooking stoves and I do hereby declare the following to be a full and exact description of the same reference being had to the annexed drawings which form part of this specification in which Fig 1 is a view of the front of the place showing the front fire doors.

Fig 2 is a view of the side of the stove.

represented at (a) and the panel (a') is the counterpart of it.

The fire door is ornamented by a figure (b) of Hercules with the skin of the Nemean Lion thrown round his loins, his club resting on the ground and against him, while Hebe (probably) attended by another female is about to pour out some Nectar into a dish which Hercules holds. The panel (b') is ornamented with the counterpart of (b).

The oven door (Fig. d) consists of a moulding surrounding a panel in which is a radiating ornament with an elliptical border, which is surrounded by scrolls terminating in a flower, this is shown at (h) by one quarter of the ornament, the balance being merely counterpart. The panel at the end of the fire place or chamber is ornamented with a rosette somewhat elaborated (euc) from which four scrolls (d, d, d, d) diverge into the corners of the square head (i) which surrounds this device. The panel on the other corner at the upper back part of the side of the stove is ornamented by an eagle (e) in the centre - above whose head a ribbon (f) with the inscription "Ne plus ultra" is placed below the eagle and rising up on either side a pair of cornucopias with fruit &c. (g)

Having thus described, and represented my design for stoves. What I claim therein as new and desire to secure by Letters Patent is the combination of the above ornaments arranged as described.

In testimony whereof I have hereunto set my hand before two subscribing witnesses.

James Leffel
